UNITED STATES PATENT OFFICE.

CYRUS W. BALDWIN, OF CHICAGO, ILLINOIS; ASSIGNOR TO WILLIAM E. HALE, OF SAME PLACE.

GAS-ENGINE.

SPECIFICATION forming part of Letters Patent No. 276,747, dated May 1, 1883.

Application filed October 20, 1882. (No model.)

To all whom it may concern:

Be it known that I, CYRUS W. BALDWIN, a citizen of the United States, residing in the city of Chicago, Cook county, State of Illinois, have invented certain new and useful Improvements in Gas-Engines, of which the following is a specification.

An objection to the use of ordinary gas or explosive engines for many purposes is the necessity of starting them by hand, or by some power stored up for the purpose.

To avoid the necessity of constant attendance and manipulation, or of using a secondary starting-engine operated by power derived from the operation of the main engine, I use means whereby a charge of explosive gases may be carried into the explosion-cylinder while the engine is at rest, and there exploded to impart the initial movements. I propose to use different means for effecting this result. One, which is simple and effective, is illustrated in the drawings—in section in Figure 1, in plan, Fig. 2, and in detail, Fig. 3.

As shown, the engine is similar in many of its features to that for which I made application for Letters Patent August 10, 1882—that is, there is an explosion-cylinder, A, containing a piston, B, connected by a pitman to the crank of a shaft, C, a compression-cylinder, D, shorter and broader than the main cylinder, and provided with inlet air and gas ports, and with a piston, the rod E of which is connected with an eccentric, E', through the medium of a pitman-rod, E². The air and gas mixed are drawn into the cylinder D, forced through a channel, e, into the cylinder A, and exploded when the piston B uncovers an igniting-opening, e, a check-valve at f in the passage e closing on its seat to obstruct said passage at the time of the explosion. On the forward movement of the piston in the direction of its arrow a valve, h, in the piston is opened to permit the waste gases to pass through a channel, g, in the piston, and out at one side to a port, w, leading to a pipe by which the gases are conducted to a reservoir, A', or elsewhere. The movements of the valve h are regulated from the pitman or connecting rod b, which has upon it a finger, a, opposite an arm, j, on the end 50 of the valve-rod h', so that as the pitman de-

scends below a horizontal line the rod h' will be moved back and the valve lifted. A spring, k, may be used to return the valve to its seat; or a positive connection of any suitable kind may be made with the pitman. Any other device for opening the valve h positively may be employed.

The pitman E² is connected to the piston-rod E through the medium of a link, E⁴, forming part of the piston-rod, and having a triangular opening, through which passes the cross-pin v of the pitman. The rear edge, x, of the opening in the link coincides with the periphery of a circle having the axis of the shaft C as its center. The other edge, x', is at an angle of about thirty degrees to the edge x.

A brake-lever, Z, having a limited motion, extends below the fly-wheel Y, and an arm, W, embracing at its rear end an eccentric, m, on the shaft C, has a shoulder, y, adapted to catch beneath the end of the brake-lever Z. The arm W is suspended from the pitman E² by a link or chain, u, or otherwise, so that it will have a limited downward motion, but be capable of rising under the action of the governor connected to it in any suitable manner. As shown, a link, p, slotted to receive a pin, p', on the arm W, is connected to a lever, F, the opposite end of which is attached to the rod H of the governor.

During the movement of the engine under the successive explosions of the mixed gases there is nothing peculiar beyond what has already been set forth, the pin v of the pitman being at the upper end of the link E⁴, the arm W being suspended from the pitman E², away from contact with the brake-lever Z, and the link p playing freely on the pin p' under the action of the governor.

When it is desired to arrest the engine in position for automatic starting, the pitman E² is thrown down until its pin v rests on the horizontal edge of the opening in the link, when the piston-rod E will be drawn out to its full extent (shown in full lines, Fig. 3) by the backward movement of the pitman, drawing a charge of mixed gases into the cylinder D. As the shaft C continues to revolve, the pin v slides back and forth upon the horizontal edge of the link-opening without changing the

position to which the charging-piston has been set. As the pitman is lowered the link u descends, and the arm W would fall upon the brake-lever if it were not held up by the link p ; but as the governor-balls drop as the engine slows, the link p will be carried downward, and the shoulder y of the reciprocating arm W will finally catch upon the end of the brake-lever and draw the brake-shoe against the fly-wheel, arresting the rotation thereof. As the brake cannot be applied until the engine has nearly ceased its motion, the movement will be at once arrested on the application of the brake, so that the engine is made to stop at the predetermined point—that is, with the main piston B just back of the igniting-hole c , and with the pin v at the forward end of the opening in the link, the gas-jet being lighted.

The engine can at any time be started by lifting the loose end of the pitman E^2 , which releases the brake and brings the pin v upon the inclined edge x' of the link E^4 , thus moving forward the piston-rod E and its piston to the position shown in dotted lines, Fig. 3, so as to force a charge of gases into the main cylinder, where they will be ignited by the gas-flame, and by their explosion will impart the necessary initial movements to the engine. By thus arresting the engine always at the same point with a charge in the compression-cylinder, and by expelling the latter and forcing it into the main cylinder and igniting it without turning the main shaft, I am enabled at any time to start the engine with the application of but such slight power as is generally required to impart motion to engines driven by steam, air, &c., where it is necessary only to turn a cock or move a lever.

I wish it to be understood that while the above-described novel devices are most effective I do not limit myself to their use, as the principles of my invention may be embodied in other devices. For instance, other hand devices than those described may be used for forcing a charge into the cylinder after the parts have been arrested in the proper position. For instance, a pitman in two jointed sections capable of being brought into line or bent at an angle may be substituted for the pitman and link described, the charge may be ignited by an electric spark generated on the raising of the pitman, and exploding the gases or igniting a gas-jet which explodes the gases, and wholly different brake and governing mechanism for stopping the engine at the desired point will occur to any practical mechanician. The pitman will be set by different means, according to the application of the engine. When used for lifting elevator-cars, the pitman is connected to the hand-rope Q of the elevator, so as to be operated from the car.

It will be obvious that in some cases—as in light engines—the brake may be operated without the interposition of the governor, and that the appliances for arresting the com-

pression-piston when the cylinder is full may be used without the brake, the fly-wheel being loaded to bring the parts to rest always in the same position.

I do not abandon or dedicate to the public any patentable features set forth herein and not hereinafter claimed, but reserve the right to claim the same, either in a reissue of any patent that may be granted upon this application, or in other applications for Letters Patent that I may make.

I therefore claim—

1. The combination, in a gas-engine, of appliances for arresting the motion with the parts always in the same position, and hand devices for forcing a charge of gases into the main cylinder and there exploding it, without any movement of the main engine, substantially as set forth. 80

2. The combination of the arresting devices constructed to always stop the engine with a charge in the compression-cylinder, and appliances for expelling said charge into and exploding it in the main cylinder without first operating the main piston, substantially as set forth. 90

3. The combination of the main cylinder and piston, having an igniting-opening and constant flame, or its equivalent, and the charging-cylinder, and appliances whereby the engine is automatically arrested with a charge in the charging-cylinder, and with the main piston at the rear of the igniting-opening, substantially as set forth. 95

4. The combination, with the charging-cylinder and appliances for operating its piston, of an intermediate connection constructed to permit the piston to be thrown out of control of such appliances after the charge is in the cylinder, and to expel said charge by the act of restoring such parts to position, substantially as set forth. 105

5. The combination of the charging-cylinder, piston and piston-rod, the pitman driven from the main engine, and intermediate link-connection constructed to permit a play of the pitman independently of the piston, as and for the purpose set forth. 110

6. The combination of the cylinder D , its piston, rod, and link, having a triangular opening, and the pin v , extending through said opening, substantially as set forth. 115

7. The combination of the charging-cylinder, pitman and intermediate adjustable connection, and a brake and appliances for operating it upon the change in adjustment of the said connection, whereby the brake is removed when the charge is expelled from the cylinder, substantially as set forth. 120

8. The combination, with a gas-engine, of a brake and appliances, substantially as set forth, whereby the brake is applied automatically to arrest the motion of the engine when the charging-cylinder is full, substantially as specified. 125

9. The combination, with a gas-engine, of a brake device and appliances constructed to

apply the brake when the parts are in a pre-determined position, and a governor and connections whereby the said appliances are held out of operation until the momentum of the engine is nearly exhausted, substantially as set forth.

10. The combination of the adjustable pitman and link-connection, brake-lever Z, reciprocating catch-arm W, suspended from the pitman, and governor and connections be-

tween the same and the arm W, substantially as set forth.

In testimony whereof I have signed my name to this specification in the presence of two subscribing witnesses.

CYRUS W. BALDWIN.
